(57) **CLAIM**

The ornamental design for a cap for microtube, as shown and described.

DESCRIPTION

FIG. 1 is a top perspective view of a cap for microtube in accordance with the present design;

FIG. 2 is a top plan view thereof;

FIG. 3 is a front side elevation view thereof;

FIG. 4 is a rear side elevation view thereof;

FIG. 5 is a left side elevation view thereof;

FIG. 6 is a right side elevation view thereof; and,

FIG. 7 is a bottom plan view thereof.

The dot dash dot broken line in FIG. 2 depicts the boundary of the claim and form no part thereof.

The dash lines depict portions of the cap for microtube that form no part of the claimed design.
